LIQUID AND PASTE DETERGENT
CONCENTRATES

Werner Stein, Erkrath-Unterbach, and Wilfried Umbach and Horst Baumann, Hilden, Germany, assignors to Henkel & Cie, GmbH, Dusseldorf, Germany, a corporation of Germany

10 Claims. (Cl. 252—121)

ABSTRACT OF THE DISCLOSURE

There is disclosed a novel method for reducing the viscosity of liquid and/or paste detergent concentrates containing an olefin monosulfonate. The process lies in the finding that by incorporating into the paste and/or liquid detergent concentrate a surface active olefin disulfonate the viscosity of the concentrate is significantly reduced and in addition the wetting and cleansing activity of the wash active materials present in the detergent are enhanced. The invention also includes the resultant concentrates characterized by reduced viscosity.

This invention relates to a method and composition for the reduction of the viscosity of liquid or paste detergent concentrates by means of an olefin disulfonate.

Liquid or paste detergent concentrates are not only used in compounded form as liquid washing, cleaning or rinsing agent, but also are regularly used as intermediates in the industrial production of corresponding washing powders. Such concentrates frequently have a high viscosity which makes their industrial utilization difficult, especially their conveyance or admixing with other components, as well as handling them in daily use upon dosaging or diluting with water. These difficulties encountered with high viscosity are particularly noticeable in detergent concentrates containing surface-active monoolefin sulfonates. Surface-active monoolefin sulfonates include sulfonation products obtained from the reaction of aliphatic monoolefins of a chain length of C_8 to C_{24} with strong sulfonating agents such as oleum, chlorosulfonic acid or sulfur trioxide followed by hydrolysis, the manufacture of which is described, for instance, in U.S. Patents 2,061,617 to 2,061,620 and 2,094,451.

It has been attempted frequently to improve the viscosity of liquid or paste detergents by adding anionic hydrotropic substances such as the sulfonates of benzene, toluene or xylene. These substances, although they increase the water-solubility of the wash-active substances and materials admixed with detergent solutions or pastes, have only a slight viscosity-reducing effect on the concentrated aqueous pastes; and furthermore, they do not exert any washing or wetting action in contrast to the surface-active monoolefin sulfonates and disulfonates.

It is therefore an object of this invention to overcome these and other difficulties in addition to providing a method and composition for reducing the viscosity of liquid or paste detergent concentrates. It is a further object of this invention to provide a method and composition for the viscosity-reduction of olefin sulfonates or olefin disulfonates in combination with other wash-active materials. It is a further object of this invention to provide a method and composition for facilitating conveying, dosaging, admixing or diluting liquid or paste detergent compositions. It is a further object of this invention to assist the wetting and cleaning action of wash-active materials present in liquid or paste detergent concentrates.

These and other objects have been achieved by the method and composition of the present invention, in

2

which an olefin disulfonate is used to reduce the viscosity of liquid or paste detergent concentrates, especially those concentrates in which an olefin sulfonate is employed. The surface-active olefin disulfonates of this invention cannot only substantially reduce the viscosity of the concentrated solutions and pastes, but it also assists the wetting and cleaning action of the wash-active materials present in the detergent concentrate.

The composition of the present invention comprises liquid or paste detergent concentrates containing monoolefin α -sulfonates of a chain length of C_8 to C_{24} and preferably of C_{10} to C_{20} , and at least one other anionic or non-ionic wash-active material characterized by a total content of surface-active, wash-active material of 10 to 60 percent by weight and an amount of 0.5 to 25 percent by weight, preferably 1 to 15 percent by weight of olefin disulfonate referred, in each case, to the weight of solution or paste. The monoolefin disulfonates, which serve to reduce the viscosity of the aqueous detergent concentrate are characterized by a chain length of C_8 to C_{24} , and preferably C_{10} to C_{20} , and by two sulfonate groups in the molecule, and are obtained by reacting monosulfonates of monoolefins with sulfur trioxide.

The preparation of the monoolefin sulfonates of this invention is effected through sulfonation of monoolefins with SO_3 or chlorosulfonic acid and subsequent saponification, which is generally described in U.S. Patents 2,061,617 to 2,061,620 and 2,094,451. By using 0.5 to 1 mol SO_3 , referred to 1 mol of monoolefin, essentially monosulfonates are formed, whereas, by using 2.2 to 2.6 mols SO_3 , referred to 1 mol of monoolefin, disulfonates are almost exclusively formed.

The total concentration of organic wash-active material in the liquid detergent concentrates and pastes of the invention can lie within the range of 10 to 60, and preferably 10 to 50 percent by weight, referred to the weight of the entire solution or paste. The quantitative ratio by weight of olefin sulfonate to olefin disulfonate is advisedly between 20:1 and 1:4, and preferably between 10:1 and 1:2. In the preferred range, the viscosity-reducing action of the olefin disulfonates is particularly effective. The total content of sulfonated and disulfonated olefins in the concentrates should be 5 to 40 percent by weight.

In addition to the olefin sulfonate and olefin disulfonate, the concentrates also contain at least one other anionic or non-ionic surface-active wash-active material such as alkali soaps of fatty acids as well as wash-active materials of the sulfate or sulfonate type, such as primary or secondary alkyl sulfonates, sulfated alkyl polyglycol ethers, sulfate alkyl phenol polyglycol ethers, alkyl benzene sulfonate, α -sulfo-fatty acid esters, and the like. Suitable non-ionic wash-active materials are alkyl polyglycol ethers, alkyl phenol polyglycol ethers and fatty acid condensation products comprising esters and amides. The amount of such wash-active materials in the concentrates is at least 5 percent by weight and preferably 10 to 45 percent by weight, referred to the weight of the solution or paste.

The olefin monosulfonates, olefin disulfonates and the other anionic wash-active raw materials contained in the concentrates can be used as sodium, potassium or ammonium salts or else as salts of organic bases, such as mono-, di- or triethanolamine. The said salts or cations can also be present in mixture, which is frequently advantageous for the preparation of highly concentrated clear solutions.

Due to their reduced viscosity, the detergent concentrates in accordance with the invention, are particularly suitable for the incorporation of components and addition substances customarily used in washing and cleaning agents. These include the wash-alkalis such as carbonates

and pyro-, poly- and metaphosphates, as well as the silicates of alkalis. The known organic chelate formers, e.g., ethylenediamine-tetracetic acid and its equivalents, can also be incorporated in the concentrates of the invention. Finally, organic high-molecular colloid substances, particularly water-soluble derivatives of cellulose or of starch as well as water-soluble salts of polyacrylic acid or polymethacrylic acid can be added to them. If the concentrates are to be used directly as detergent or cleaning agents, they can also contain known solvents, such as monohydric or polyhydric alcohols, polyglycols or polyglycerins. As additional components, there enter into consideration coloring substances and perfumes, optical brighteners, skin-protecting substances and stabilizers.

The following non-limiting examples are given as certain preferred embodiments of the invention and are not to be construed as narrowing the novel viscosity-reducing method and composition.

These examples illustrate the viscosity-reducing effect of the diolefin sulfonates on various detergent concentrates.

Various combinations of olefin disulfonates and olefin sulfonates with wash-active substances are prepared with water and the viscosity of the various combinations measured. The nature of the compositions thus prepared and the results obtained are reported in the tables below.

The monoolefin sulfonates and monoolefin disulfonates used in the following Examples I to IX contain 14 to 18 carbon atoms in the molecule (average chain length C₁₆) and are in the form of sodium salts. A Na-alkyl benzene sulfonate having an unbranched alkyl chain (average chain length C₁₂) was also used. The alkyl sulfate of Example VI comprises the sodium salt of a sulfated fatty alcohol of a chain length of C₁₂ to C₁₈ (average chain length C₁₅). The "Texapon N" (registered trademark) of Examples IV and V is the sodium salt of a coconut fatty alcohol of an average chain length of C₁₂ to C₁₈, which is reacted with 2 mols of ethylene oxide and thereupon sulfated. The alkyl polyglycol ether of Examples VII and IX is obtained by addition of 10 mols of ethylene oxide to a fatty alcohol of a chain length of C₁₆ to C₁₈ and an iodine number of 50. The sulfo-ester of Example VIII is the sodium salt of an α-sulfo-fatty acid methyl ester from hydrogenated palm nut fatty acid. The soap of Example IX is a sodium soap of saturated fatty acids of a chain length of C₁₂ to C₂₂ (average chain length C₁₈).

The viscosity of the aqueous solutions is measured in each case at a temperature of 20° C. after standing for three weeks, by means of a Höppler drop-ball viscosimeter (DIN 53,015) in Examples I, III to V and VII to XI, and with an Epprecht rotary viscosimeter [I. R. van Wazer et al., *Viscosity and Flow Measurement*, Interscience Publishers, (New York 1963), pp. 129-135] in Examples II and VI. The percentages set forth in the tables are percentages by weight.

The alkyl benzene sulfonate/olefin sulfonate/olefin disulfonate system is examined in different mixture ratios, the concentration of the total solution being maintained constant in Example I, the concentration of the alkyl

benzene sulfonate being maintained constant in Example II and the concentration of the alkyl benzene sulfonate and of the olefin sulfonate being maintained constant in Example III. From Examples II, VIII and IX, it can be seen that the viscosity of detergent solutions can rise considerably upon the addition of olefin sulfonates. This phenomenon is only partly due to the increase in the concentration of the wash-active material in the solution. For example, the viscosity of the 40-percent alkyl benzene sulfonate solution is 4650 centipoises and that of a 40-percent olefin sulfonate solution is 1100 centipoises. A solution containing 30 percent alkyl benzene sulfonate and 10 percent olefin sulfonate would theoretically have to have, by application of the mixture rule, a viscosity of about 3700 centipoises, as compared to an actually found value of 9000 centipoises. In the same manner as in all other examples, an addition of disulfonate or a replacement of monosulfonate by disulfonate led in this case also to a strong drop in the viscosity of the aqueous detergent solutions, which was not predictable from the viscosities of solutions of the individual wash-active components of the mixture. The viscosity-reducing effect obtained according to the invention, therefore, is synergistic.

Thus, there has been described a novel composition and method for reducing the viscosity of liquid or paste detergents by means of an olefin disulfonate comprising from 8 to 24 carbon atoms. These disulfonates are particularly effective when used in combination with detergent solutions or pastes that also contain monoolefin sulfonates.

Although the invention has been described with reference to certain preferred embodiments, it is not the intent of the applicant to be limited thereby, and certain modifications of the novel composition and method are intended to be included within the broad scope of the invention, as embodied in the following claims.

What is claimed is:

1. A paste or liquid detergent concentrate consisting essentially of an α -monoolefin monosulfonate containing 8 to 24 carbon atoms and an α -olefin disulfonate containing 8 to 24 carbon atoms as viscosity reducing agent, said α -olefin disulfonate being present in an amount of from 0.5 to 25% by weight of said detergent concentrate.

2. A paste or liquid detergent concentrate according to claim 1 wherein said α -olefin disulfonate is present in an amount of from 1 to 15% by weight of said detergent concentrate.

3. A paste or liquid detergent concentrate according to claim 1 wherein said α -monoolefin monosulfonate and said α -olefin disulfonate each contain 10 to 20 carbon atoms.

4. A paste or liquid detergent concentrate according to claim 1 additionally containing at least one other wash active material selected from the group consisting of organic anionic and nonionic detergents, the total amount of monosulfonate and disulfonate and wash active materials present in said concentrate amounting to 10 to 60% by weight of said concentrate.

5. A paste or liquid detergent concentrate according

to claim 4 wherein the total amount of surface active and wash active materials amounts to 50% by weight of said concentrate.

6. A paste or liquid detergent concentrate according to claim 4 wherein said α -monoolefin monosulfonate and said α -olefin disulfonate are present in a total amount of 5 to 40% by weight of said concentrate.

7. A paste or liquid detergent concentrate according to claim 4 wherein said α -olefin monosulfonate and said α -olefin disulfonate are present in a ratio of from 20:1 to 1:4 by weight.

8. A paste or liquid detergent concentrate according to claim 4 wherein said α -olefin monosulfonate and said α -olefin disulfonate are present in a ratio of from 10:1 to 1:2 by weight.

9. A paste or liquid detergent concentrate according to claim 4 wherein said additional wash active material is at least one member selected from the group consisting of alkali soaps of fatty acids, alkyl sulfates, alkyl polyglycol ether sulfates, alkyl benzene sulfonates, α -sulfo fatty acid esters, alkyl polyglycol ethers and alkyl phenol polyglycol ethers.

10. A paste or liquid detergent concentrate according to claim 4 additionally including at least one further member selected from the group consisting of alkali metal carbonate, organic chelating agent, a water-soluble derivative of cellulose or starch, water-soluble salts of polyacrylic acid or polymethacrylic acid, a solvent, a perfume, and an optical brightener.
